UNITED STATES PATENT OFFICE

SIMON MYERSON, OF BROOKLINE, MASSACHUSETTS

DENTAL ANCHORAGE

Application filed November 6, 1929. Serial No. 405,078.

This invention relates to improvements in the art of dentistry and more particularly to dental clasps or anchorages designed to be secured upon the crown of a natural tooth for the purpose of affording an anchorage for adjacent artificial teeth, bridge work, or orthodontic appliances.

Heretofore and prior to this invention, considerable difficulty has been encountered in the attachment of suitable anchorages to natural teeth, the anchorages ordinarily constructed for this purpose being incapable of secure attachment without grinding the natural tooth or otherwise injuring or destroying natural tooth tissue. It is among the principal objects of this invention to provide an anchorage of such construction that it may be slipped over the belly or swell of the tooth crown and become securely fixed upon said crown to closely fit the same at the neck thereof, all without necessitating any grinding or other such treatment of the natural tooth.

A further object of the invention is the provision of an anchorage, the normal shape of which corresponds to the general external contour of a natural tooth crown, the anchorage being in the general form of an annulus when completed having openable portions in the gingival portion thereof, the construction of the anchorage being such as to wholly eliminate the necessity in many cases and to greatly reduce in all cases the necessity of grinding the natural tooth.

A still further object of the invention is the provision of a dental anchorage or clasp which is characterized by the provision of openable wing portions in the gingival portion thereof, the proximate edges of said wing portions being provided with means for effecting interlocking engagement therebetween to securely fix the anchorage or clasp upon the crown with the gingival edge thereof closely embracing the gingival margin of the tooth crown.

Other objects and advantages of the invention will appear more fully hereinafter.

The invention consists substantially in the construction, location, arrangement and relative location of parts, all as will appear more

fully hereinafter, as shown in the accompanying drawing and as finally pointed out in the appended claims. In the accompanying drawing, wherein I have shown for purposes of illustration several preferred forms of the invention:—

Figure 1 is a view showing a tooth to which has been attached one form of anchorage embodying the principles of this invention;

Figure 2 is a perspective view of the anchorage shown in Figure 1;

Figures 3, 4 and 5 are perspective views of modified forms of anchorages embodying the principles of this invention;

Figures 6 and 7 are views showing the application of anchorages embodying the principles of this invention to front teeth;

Figure 8 is a still further modified form of clasp adapted for use in connection with the tooth shown in Figure 1;

Figure 9 is a perspective view of a dental clasp of the form shown in Figures 6 and 7 but showing a modified arrangement of interlocking means;

Figure 10 is a plan view of a substantially flat strip or pattern from which an annulus may be formed to provide an anchorage embodying the principles of the present invention; and

Figure 11 is a perspective view showing the flat strip shaped to the form of an anchorage.

Referring now to the drawing and more particularly to Figures 1, 2 and 7, it will be seen that the invention in one form thereof 85 contemplates the provision of an anchorage 10 intended for attachment to the crown 11 of a natural tooth, such as the molar or bicuspid or front tooth. It is, of course, well known that the crowns of natural teeth such as that shown in Figures 1 and 7 are in almost all cases formed with outwardly bulging walls with the result that it has been a difficult problem to rigidly secure an anchorage thereon so that it closely fits the tooth irrespective of differences in the horizontal diameters thereof unless resort is had to grinding down the bulge or swell of the tooth crown.

To meet this problem the present anchorage 10 is constructed in the form of an annulus 100

or band or strip of metal, the axial wall 13 of which is contoured to correspond generally to the curvature of the axial surfaces of the tooth crown 11. Inasmuch as the diameter 5 across the gingival edge 14 of the band 10 is less than the maximum bucco-lingual diameter of the crown 11, it would be impossible to slip the band over the crown into the position shown in Figure 1 and accordingly the 10 band is provided in the portion adjacent the gingival edge thereof with a pair of openable wing members 15 and 16 which open outwardly to permit the band to be slipped into proper position over the tooth crown.

15 As appears most clearly in Figure 2 these wings 15 and 16 are formed by providing a T-shaped cut in the buccal or lingual surface, the vertical free edges 17 of the wings being arranged to meet each other when said wings 20 are brought into closely fitting engagement with the axial surface of the crown. The horizontal edges 18 of the wings preferably overlap the horizontal edge 19 of the T-shaped cut in order to leave no surface of the tooth 25 crown exposed between opposite edges of the band. The overlapping of the edges 18 and 19 may be accomplished, in one instance, by striking and so drawing the edges 18 axially of the band to an extent sufficient to enable 30 them to overlap the edge 19 of the band.

In order to lock the band 10 securely in position when the same has been slipped over the tooth crown the wings 15 and 16 are respectively provided with complementally 35 formed interlocking elements. One of these elements is secured to the free edge of the wing 15 and is in the form of a T-shaped or dovetail extension having a stem 20 and a head 21 at one end thereof, the opposite end 40 of the stem being permanently secured, as at 22, to the external surface of the wing 15 in any suitable manner, preferably by soldering, or it may be integral therewith. Secured to the opposite wing 16 of the band or formed 45 integrally therewith is a block 23 which is provided in the external surface thereof with a T-shaped recess 24 within which is adapted to be received the T-shaped locking element 20-21. It will be observed that when the 50 wings 15 and 16 are brought into close embrace with the gingival or neck portion of the tooth crown such that the free vertical edges thereof meet and the horizontal edges 18 thereof overlap the element 20-21 is received within its seat 24 whereby to securely 55 lock the wings into the position shown in Figure 1. For aesthetic reasons the band 10 may be cut out, as at 25, in the wall thereof which presents toward the cheek or lip of the 60 patient. It is important to note, however, that even though the band is provided with openable wings and with the cut-out 25 the band is still in the form of a circumferentially 65 complete annulus one-half of which constitutes the portion immediately above the wings

15 and 16 and the other half of which constitutes the portion immediately below the cut-out 25.

Figure 3 shows a modified form of interlock between the openable wings 15 and 16. In this modified arrangement the wing 15 is provided in the external surface thereof adjacent its free end with a headed protuberance, or knob 26. The opposite wing 16 is in turn provided with a leaf 27 one end of which is secured permanently in position, preferably by soldering, as at 28, or formed integrally therewith. Provided in the portion of the leaf extending beyond the free edge 17 of the wing 16 is an opening 29 which is adapted to receive the headed protuberance 26 of the wing 15 when the wings are brought into close embrace with the neck or gingival portion of the tooth. It will be observed in the form of band shown in Figure 3 that there is no cut-out portion like that indicated by the numeral 25 in Figure 2.

In order to facilitate closure of the wings 15 and 16 for interlocking engagement between the locking elements thereof each wing 40 may be provided with a gold wire 30 one end of which is secured, as by soldering, to the wing, as at 31. These wires 30 may be twisted together in order to bring the free vertical edges of the wings into abutting relation 45 whereupon the interlocking elements thereof may be brought into operative association for positionally securing the band upon the tooth crown. It will be understood that the wires 30 may be employed in conjunction 50 with the interlocking means shown in Figure 1 as well as with any other type of interlocking means, such as are shown in Figure 4 to be now described. When the interlocking 55 elements have been brought into engagement with each other the wires 30 may be removed from the band by grinding the same off therefrom. Obviously, other means may be employed in lieu of the wires 30 for the purpose specified.

Referring to this Figure 4 it will be observed that the wing 15 is provided with a locking element 32 the freely projected end 33 of which is enlarged and provided centrally thereof with an opening 34. Provided upon the wing 16 or formed integrally therewith is a block 35 having a recess 36 of a shape adapted to receive the enlarged head 33 of the interlocking element 32. Provided within the recess 36 is a headed knob or protuberance 37 which is receivable within the opening 34 of the interlocking element 32 when the latter is received within the recess 36. In each of the structures shown, with the exception of that shown in Figure 3, it will be understood that when the wings 15 and 16 are locked together in the manners described the interlocking devices will be substantially flush leaving only the knob 37 to be ground flush by sand paper discs or

by other means, either in the mouth or before hand so that the external surfaces thereof will be smooth and unobtrusive. The locking members 27 (Figure 3), 32 (Figure 4), 20 5 (Figure 2), etc., are all preferably flush at their marginal edges with the wing surfaces to which they are secured.

The structure shown in Figure 5 differs from those hereinbefore described in that 10 the horizontal edges 18 of the wings are not shaped or formed to overlap the proximate edge 19 of the band. In a structure such as this a portion of the axial surface of the tooth crown is exposed between edges 18—18 15 and 19 of the band. It will be understood, of course, that any one of the forms of interlocking devices hereinbefore referred to may be employed in connection with the structure shown in Figure 5.

20 Figure 8 shows still another form of clasp or band employing the interlocking means shown in Figure 4, although any one of the other forms of flush-type interlocking means may be employed. In the structure shown

25 in Figure 8 it will be observed that the edge of the band which is adapted to underlie the horizontal edges 18 of the wings 15 and 16 is provided with a circumferentially extending shoulder or rabbet 38 whereby to insure

30 a flush joint between said edges 18 of the wings and the portion of the band which they overlap. If desired, a cut-out may be provided in the wall of the band shown in Figure 8 which is similar in all respects to

35 the cut-out portion 25 of Figure 2. It will be understood, of course, that the openable wing portions of the band and their associated interlocking elements may be formed in the buccal or lingual walls of the band, 40 although it is preferable, as mentioned above that they be positioned at the buccal side of the tooth crown. It will be seen that whereas in Figures 3, 5 and 8 the annulus is circumferentially complete in the occlusal portion

45 thereof, this is not so in the case of the structures shown in Figures 2 and 4 wherein the annulus is circumferentially complete in an oblique direction extending from the occlusal portion of the band at the winged side thereof to the gingival portion thereof at the side 50 diametrically opposed to the winged side.

The interlocking means may be formed as integral parts of the band or they may be separately secured thereto, as by soldering or the like. Furthermore, the band may be provided with a top, as in the case of the usual 55 gold crown, to cover the cusps of the tooth or it may not. For purposes of avoiding all grinding, it is preferable to provide the band without an occlusal surface. Nor is it necessary to provide a cut-out in the buccal wall 60 of the band such as is shown in Figures 2 and 4.

65 While the structures hereinbefore described illustrate the use of interlocking

means in bands or strips adapted for bicuspids or molar teeth, it will be seen by reference to Figures 6, 7 and 9 that the same means may be employed for locking a band upon the front or incisor teeth. Figure 9 illustrates in perspective a form of anchorage for use in connection with an incisor. In this form of anchorage it will be observed that the lingual wall 39 thereof is intact and that the incisal edge thereof is inturned, as at 40, to overlap to some extent the labial surface of the tooth adjacent the incisal edge thereof. The labial surface of the anchorage is cut-out in such manner as to provide a circumferentially extending portion 41 which is adapted to embrace the gingival portion of the tooth. The circumferential portion 41 of the anchorage is slit in the labial wall thereof, as at 42, to provide a pair of openable wing portions 43 and 44 which are respectively provided with the interlocking means designated generally by 45, this means being substantially similar to the interlocking means shown in Figure 3. Figure 6 shows an anchorage which is similar in every respect to that of Figure 9 with the exception that in place of the interlocking means shown in the latter figure the interlocking means of Figure 2 are employed. In both Figures 6 and 9 the interlocking means are provided in the labial wall of the clasp adjacent the gingival edge thereof. Figure 7 illustrates the use of the interlocking means employed in the structure shown in Figure 4. While Figures 6, 7 and 9 illustrate the employment of the openable wing portions and their associated interlocking elements in the labial wall of the anchorage, it will be understood that these interlocking wings may be formed in the lingual wall of the anchorage adjacent the gingival edge thereof and that the horizontal edges 46 thereof may be shaped to overlie the proximate horizontal edge of the wall of the crown, as in the case of the structures shown in Figures 2, 3, 4 and 8.

It will be understood that each of the anchorages hereinbefore described may be attached to its respective tooth crown without employing any adhesive material. In order, however, to provide for a more permanent attachment it is preferable to employ cement, 110 gutta-percha or other such adhesive material in conjunction therewith. In forming an anchorage embodying the principles of this invention the procedure is substantially as follows. An accurate impression is initially 115 taken of the tooth crown upon which the anchorage is to be secured. A hard metallic die is then obtained from this impression and an anchorage is selected of a size and shape to fit as nearly as possible this individual die. The 120 openable wing portions of the band will of necessity open outwardly as the band is forced over the region of greatest diameter of the tooth crown. The wings are then 125 drawn into position to snugly embrace the 130

gingival or neck portion of the tooth crown with the free vertical edges thereof preferably abutting each other although they may be made to overlap. The interlocking elements are then secured together. If the band is too large for its individual die the portion thereof opposite the winged portions may be slit to permit the band to intimately engage the tooth crown throughout the entire extent of the axial surfaces thereof. The band is then placed in a swedger and swedged to perfectly fit the die. The slit portion, if a slit has been provided, is then soldered. After the slit portions, if any, are permanently joined together the band is then adapted to be fitted over the particular tooth crown for which it is to be used. While the anchorage is specially designed to carry a bridge, orthodontic or other dental appliance it may also be used independently to cover an individual tooth.

While in the preceding descriptions the anchorage in its several forms has been described as being in the form of a circumferentially complete annulus, it may, in some instances, be formed initially in the shape of a substantially flat strip or pattern 46, as appears most clearly in Figure 10. This strip 46 is provided, preliminarily to shaping it into annulus form, with the wing element 47-47 and their associated interlocking devices 48 in the gingival portion of the strip. To form the strip into the desired annulus it is merely necessary to bring the edges 49-49 thereof into overlapping engagement, as shown in Figure 11, for subsequent soldering together, as at 50, thereby providing a circumferentially complete annulus. A strip or pattern such as is shown in Figure 10 obviously reduces the number of sizes that the manufacturer would have to supply in order to meet the large variety of shapes and sizes of natural teeth. For any given natural tooth it is only necessary to modify the strip or pattern 46 to the style, shape, contour or size thereof and then complete the band by uniting the free edges 49-49 together.

It will be understood, of course, that various changes and modifications may be made in the invention from time to time without departing from the principles or real spirit of the invention and it is accordingly intended to claim the invention broadly, as well as specifically, as indicated in the appended claims.

What is claimed as new and useful is:

1. A dental anchorage arranged to encompass the crown of a tooth, said anchorage being in the form of a circumferentially complete annulus the wall of which is contoured to the external curvature of the axial surfaces of the tooth crown, a pair of openable wing members provided in the gingival portion of the annulus, the circumferentially extending edges of said wing members opposite the gin-

gival edges thereof being formed to overlap the proximate edge of the annulus, and means for locking said wings snugly about the neck of the tooth.

2. A dental anchorage arranged to encompass the crown of a tooth and comprising a circumferentially complete annulus, said annulus being provided in the gingival portion thereof with a pair of tongues capable of being flexed outwardly as the gingival edges thereof are forced over the crown, and a pair of wires respectively secured to each of said tongues and adapted to be twisted together whereby to bring the proximate edges of said tongues into abutting relation preliminarily to securing the same together.

In testimony whereof, I have hereunto affixed my signature.

SIMON MYERSON.
